US00D909401S

(12) **United States Design Patent** (10) Patent No.: **US D909,401 S**
Shim et al. (45) Date of Patent: ** Feb. 2, 2021

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Ahyeon Shim**, Suwon-si (KR); **Yeongseo Hong**, Suwon-si (KR); **Jangwon Seo**, Suwon-si (KR)

(73) Assignee: **SAMSUNG ELECTRONICS CO., LTD.**, Gyeonggi-do (KR)

(**) Term: **15 Years**

(21) Appl. No.: **29/703,086**

(22) Filed: **Aug. 23, 2019**

(30) **Foreign Application Priority Data**

Apr. 25, 2019 (KR) 30-2019-0019670

(51) LOC (13) Cl. **14-04**

(52) U.S. Cl.

USPC **D14/485**; D14/489; D14/492

(58) **Field of Classification Search**

USPC D14/485-495

CPC G06F 17/211; G06F 17/212; G06F 3/1251; G06F 3/0481; G06F 2203/04807

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The outer perimeter illustrated by a pair of dashed broken lines depicts a display screen or a portion thereof and forms no part of the claimed design. The remaining broken lines shown in the FIGURE depict portions of the graphical user interface that form no part of the claimed design.
